SHOE SOLE

Alfred D. Levine, Brookline, and Alex Bosman,
Revere, Mass.

Application May 7, 1943, Serial No. 486,028

6 Claims. (Cl. 36—31)

This invention consists in a composite outsole of new and improved construction and in a shoe or sandal including such improved sole in its structure.

An object of the invention is to provide a flexible light-weight, wear-resistant outsole which may be constructed of materials available to the shoe manufacturer under wartime conditions. This we have been able to accomplish and at the same time provide an outsole of individual and attractive appearance. Our novel construction also permits us to utilize with good advantage the available rationed amount of rubber or rubber-like material as toe and heel inserts in our novel sole and thus to dispose the available rubber where it will have the best effect in cushioning this shoe and providing a non-slipping treated surface.

We have discovered that a sole body of fibre or sole board may be reinforced to a remarkable degree by wrapping with a heavy woven fabric and cementing the fabric securely to the outer or tread face and edges of the sole body with the margins of the fabric brought over and cemented to the inner face of the sole, that is to say, the face concealed into the finished shoe. We thus provide the shank and forepart of the sole with a continuous wearing surface of woven fabric. Preferably this may be a closely woven cord or string fabric, treated to render it waterproof or water resistant and stout, tough and wear-resistant to a high degree.

A further feature of the invention consists in binding the transverse edges of the woven fabric reinforcing piece before it is wrapped about the sole piece in a manner above described. In this way we improve the appearance of the product, prevent raveling of the woven fabric, and facilitate repairs, since we are thus enabled to remove the toe and heel inserts for replacement without in any way disturbing or raveling the reinforcing fabric.

As another feature we provide at the toe and heel ends of each sole, or at either of them, an insert of sheet rubber or the like which is formed with a bevel inner edge that may overlap upon the woven fabric wrapped about the shank and forepart of the sole. The body of each insert is substantially the thickness of the fabric so that the tread surface of the composite sole lies substantially in a single plane, the body of each insert compensating for the thickness of the woven fabric beyond the bound edges thereof.

The sole body may extend throughout the shank and forepart of the sole or may be of full length and shouldered at each end adjacent

to the inner edge of the inserts thus providing a shank and forepart of slightly reduced width as compared to the remainder of the sole body. The woven fabric which is wrapped about this intermediate portion of the sole follows out the outline of the sole making it smooth and continuous. The inserts are herein shown as limited in length to substantially the unreduced portion of the sole body and so shaped that their outlines blend smoothly into the outline of the edges of the woven fabric.

As another feature of our improved sole we propose to cement to its inner surface of the sole body a textile layer of cloth. The marginal edges of the reinforcing woven fabric are brought over and cemented to this cloth facing and these margins together with the uncovered portion of the cloth facing between them and at both ends of the sole afford particularly good bonding surface when the outsole is cemented in place in the shoe bottom.

These and other features of the invention will be best understood and appreciated from the following description of a preferred embodiment thereof, selected for purposes of illustration and shown in the accompanying drawing in which—

Fig. 1 is a view in side elevation of the completed shoe,

Fig. 2 is a plan view of the sole body,

Fig. 3 is a corresponding view showing the woven reinforcing base partially wrapped about the sole body,

Fig. 4 is a plan view of the completed sole shown with its tread face uppermost, and

Fig. 5 is a fragmentary sectional view on the line 5—5 of Fig. 4 on a substantially enlarged scale.

The composite outsole of our invention includes in its structure an inner sole body which may be constructed of any suitable sheet material such as paper board, insole board, fibre board or the like. It is desirable that this should be tough and flexible although it need not in itself possess great tensile strength since this is supplied by a reinforcing fabric. The inner sole body may be die cut in the exact shape in the exact shape in which it is to be used in the composite sole, and while it is shown herein as being of full sole length it would be within the scope of the invention to employ a shorter sole body including not more than the shank and forepart of the sole. We prefer however, to use a full length sole body, and in Fig. 2 we have shown such a body 10 as die cut and ready for use. Preferably and as herein shown the sole body is

faced with a cloth ply 12 on its inner surface, that is to say, the surface which is concealed in the finished shoe. The facing 12 may be united by cementing or otherwise to the sheet material from which the sole body is died out so that in the dieing out operation the complete faced sole body is produced at a single operation.

Where a full length sole body 10 is employed we prefer to set off therein a shank and forepart area of slightly reduced width by means of shoulders 14 adjacent the heel end of the blank and shoulders 16 adjacent the toe end of the blank. The intermediate area defined by these two pairs of shoulders we then reinforce by wrapping about it a piece of heavy woven textile fabric 18 as shown in Fig. 3. This fabric may be closely woven of cords or strings and then treated so that it is rendered waterproof or water resistant. The closely woven fabric of this character is wear resistant to a high degree and has high tensile strength so that the reinforced sole has ample strength to withstand the strains of shoe making operations and to give the shoe a satisfactory wearing life.

Each reinforcing piece 18 is cut to length corresponding to the shouldered portion of the sole body with sufficient allowance so that it may be doubled about the edges of the sole body and have its longitudinal edges cemented to the cloth faced surface of the sole. Our reinforcing piece 18 is preferably, though not necessarily, provided with a textile binding strip or tape 20 on each end, this binding being doubled over the front and rear transverse edges of the reinforcing piece and stitched in place. The binding strip 20 not only imparts a finished appearance to the edge of the reinforcing piece where it is exposed in the shoe, but prevents raveling in use and also when the sole is in process of repair.

The reinforcing piece 18 is wrapped smoothly around the tread surface of the sole body 10, doubled over its longitudinal edges, and then cemented along the shank and forepart margins. As shown in Fig. 3 the margin of the reinforcing piece has been cemented in place along the outside shank edge of the sole while along the inside shank the margin still remains in condition preparatory to being trimmed and folded upon the cemented area 22 on the facing 12 of the sole body. The folded and cemented margins of the reinforcing piece are ordinarily spaced from each other and if necessary the reinforcing pieces may be trimmed so that the cemented margin will be of the desired width. In some cases it is desirable to supply a filler between these cemented edges in completing the shoe in order to maintain the bottom in flat condition, but that depends upon the thickness of the reinforcing fabric.

The sole is completed in the form herein illustrated by supplying a heel insert 24 and a toe insert 26 of rubber or rubber-like material in such a manner as to fill out and complete the tread surface of the sole. Each of these inserts is beveled upon its straight transverse edge so that it may overlap the edge of the woven reinforcing fabric 18 where it crosses the sole body. This is shown in detail in the enlarged section of Fig. 5 where it will be seen that the straight transverse edge of the toe insert 26 is undercut to form a bevel that extends rearwardly over the forward edge of the reinforcing fabric piece 18 and its binding strip 20. The insert is secured in place by being cemented to the outer

face of the sole body and by being stitched by a stitch line 28 which passes through the rear beveled edge of the insert, the sole body 10, the cloth facing 12, and the doubled margin of the reinforcing fabric 18. The heel insert 24 is similarly shaped and may be similarly secured in the organization of the composite sole. The stitch line 28 may be formed by any machine suitable for flat work such as a lock-stitch machine or a harness stitch machine such as No. 45K Singer, and for the stitch we prefer to use a stout five cord thread. The inserts 24 and 25 are wider than the reduced intermediate portion of the sole body, being shaped to register with the curvature of its wider toe and heel ends or to supplement the area of the sole body in case it is of less than full sole length.

The dimensions of the various parts are such that the doubled margin of the reinforcing fabric 18 increases the width of the reduced intermediate portion of the sole body just sufficiently to bring it smoothly into the general outline of the toe and heel portions of the sole body and of the toe and heel inserts 24 and 28. The sole 25 therefore has a smooth continuous contour so that it may be handled conveniently in stock fitting or other shoe making machinery. The thickness of the inserts is selected with reference to the thickness of the reinforcing fabric with the result that the tread surface is substantially flat. There is, as already stated, a valley between the cemented margins of the reinforcing fabric on the inner faced side of the sole, but that is concealed in the finished shoe and may be compensated for by a filler strip when necessary.

The composite sole of our invention is shown in Fig. 1 as it is used in a shoe or sandal of the play type, the upper of the shoe being formed by fabric strips 30 which are lasted above a mid-sole 32 of the platform type, supplemented by a wedge 34. The sole 32 and the under surface of the wedge 34 are leveled in a single plane and then the composite sole just described is cemented in place. We have found that the cloth facing 12 facilitates this cementing operation and the formation of a secure and reliable bond in the shoe bottom. It is understood, of course, that our composite insole is not limited in its field of use to a play type of shoe, but may be employed in shoes or sandals of any appropriate type.

An important advantage of our composite sole is that when either the toe or heel insert becomes worn down in use, it may be stripped out of the shoe bottom and replaced by a new insert without in any way disturbing the inner sole body or the reinforcing fabric which is protected during the removal of the insert by its binding strips 20.

While we have referred to the toe and heel inserts as specifically formed of rubber or rubber-like material, our invention is not limited in this respect and we contemplate employing inserts of leather or hard fibre or synthetic composition suitable from the requirements of the soles in each instance.

Having thus disclosed our invention and described certain specific embodiments thereof, we claim as new and desire to secure by Letters Patent:

1. A composite outsole unit having an integral sole body of sheet fibre board extending throughout its shank and forepart, a heavy piece of woven fabric bound at both end edges and wrapped transversely about said sole body with its margins cemented in spaced relation to the

edges of the inner face of the sole body, solid inserts beveled and overlapping the bound edges of the woven fabric at each end of the sole and of width sufficient to form a smooth continuous sole outline with the wrapped edge of the fabric, and stitching uniting the beveled edge of the inserts with the said sole body and woven fabric.

2. An outsole for leather or fabric shoes comprising a full length sole body shouldered transversely adjacent to its toe and heel ends, thereby providing a narrow intermediate portion, a heavy woven fabric wrapped about and cemented to the said narrow portion of the body and edges of the sole between said shoulders with margins overlapping and cemented to the inner face of the sole, and solid inserts extending in flush outline about the toe and heel ends of the sole body with their inner edges beveled and overlapping the transverse edges of said woven fabric.

3. An outsole for leather or fabric shoes comprising a full length sole body of fibre board shouldered in its periphery adjacent to both ends and thereby presenting an intermediate portion of reduced width, a thick, heavy water resistant woven fabric wrapped about and cemented to the outer surface and edges of said intermediate portion with its margins cemented to the inner face of the sole body, said fabric filling the edge spaces between the shoulders of the sole body and presenting a smooth outline with the end portions thereof, and beveled inserts of rubberized material secured to the ends of the sole body in overlapping relation to the ends of the woven fabric.

4. An outsole for leather or fabric shoes comprising a full length sole body of paper board having a cloth facing as its inner face, a substantially water-proof woven fabric terminating short of both ends of the sole in bound trans-

verse edges, wrapped and cemented about the tread face and edges thereof with margins overlapping and cemented to the inner cloth-covered face of the sole, and rubber sections forming the toe and heel ends of the sole and having beveled edges overlapping the transverse edges of the woven fabric, and lines of stitching passing through the beveled edges of the rubber sections and the sole body, the peripheral edges of the said sections forming in the sole a smooth unbroken outline with the wrapped edges of the woven fabric.

5. A composite outsole unit having an inner body of paper board extending throughout the shank and forepart of the sole, a heavy woven fabric co-extensive in length with the shank and forepart of the sole and doubled over the side edges of said inner body with its longitudinal margins cemented to the inner face thereof, and toe and heel inserts of rubber-like material united by stitching to the sole body and also to the ends of the woven fabric and shaped to present in the sole a smooth continuous outline with the doubled edges of said woven fabric.

25 6. A composite outsole unit having a body of paper board having a cloth facing on one side and extending throughout the shank and forepart of the sole, a woven fabric reinforcing piece of substantial thickness doubled over the side edges of said body with its longitudinal margins cemented to the cloth-faced side of the sole body, binding strips enclosing the transverse edges of said reinforcing piece and rubber-like inserts beveled and overlapping the bound edges of the reinforcing piece and wider than said sole body whereby they form a smooth continuous outline with the doubled edges of said reinforcing piece.
